United States Patent Office

Des. 187,387
Patented Mar. 8, 1960

187,387

RULER OR THE LIKE

Don E. Harley, St. Paul, and Cecil B. Woofter, Minneapolis, Minn., assignors to Arthur Salm Inc., Chicago, Ill., a corporation of Illinois

Application November 17, 1958, Serial No. 53,392

Claims priority, application Germany May 23, 1958

Term of patent 14 years

(Cl. D52—1)

Fig. 1 is a perspective view of a ruler showing our new design;

Fig. 2 is a top plan view thereof;

Fig. 3 is a side view thereof;

Fig. 4 is a bottom plan view thereof; and

Fig. 5 is an end view thereof.

The dominant features of the design for a ruler or the like reside in the portions shown in full lines.

We claim:

The ornamental design for a ruler or the like, substantially as shown and described.
